UNITED STATES PATENT OFFICE.

EDWARD J. DOLAN, OF PHILADELPHIA, PENNSYLVANIA.

FUEL.

1,025,902.

Specification of Letters Patent.

Patented May 7, 1912.

Application filed January 27, 1912. Serial No. 673,377.

To all whom it may concern:

Be it known that I, EDWARD J. DOLAN, a citizen of the United States, residing at Philadelphia, in the State of Pennsylvania, have invented certain new and useful Improvements in Fuel; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in the production of fuel and more especially fuel in the form designed for use as a fire kindler.

The invention has for its object the production of a simple, inexpensive and efficient means for the utilization of newspapers and other similar refuse material as a medium for the burning of fuel oil or other oils of a viscous nature and of proper consistency.

25 As the result of experiment, I have found that a newspaper folded and held in a compact bundle, one end of the bundle being inserted in a receptacle containing oils carefully selected for consistency, viscosity and 30 volatility. Fuel oil has been found to be the best adapted to the purpose. The bundle will take up the oil by capillary attraction, the oil thus taken up being held within spaces between the sheets, the spaces 35 being formed by the folding, in addition to the oil that is held in the body of the paper itself. When the bundle or package thus prepared is kept within a suitable receptacle for considerable time, the package will be 40 come substantial in form and, when the holding means used for retaining the bundle in shape when constructed is released, the package will still hold its form.

The essential object of the invention resides in the provision of a package of this character retained as will be hereinafter explained.

The invention is clearly illustrated in the accompanying drawing, which, with the numbers of reference marked thereon, form a part of this specification and in which drawings:

Figure 1 is a perspective view of a newspaper as it appears after the first folding in preparing it for the package, in which the paper is shown folded along a line ex-

tending transversely along the longitudinal center of the sheet. Fig. 2 is a like view in which the paper in the form shown in Fig. 1 is shown as folded by itself along the line 60 of its longitudinal center. Fig. 3 is a perspective view of the bundle complete, and Fig. 4 is a transverse section upon the line 4-4 of Fig. 3.

Reference now being had to the details of the drawings by numeral, 1 represents the newspaper from which the package is formed, the paper being first folded transversely across the longitudinal center of the sheet. The sheet is again folded along 65 the line extending through the longitudinal center of the sheet, thus producing the form shown in Fig. 2. The sheet is then folded in turn, first along a line extending through the longitudinal center of the folded sheet, 70 shown in Fig. 2, and again folded along the line extending transversely through the longitudinal center of the folded sheet and this folding repeated along lines extending longitudinally through the sheet until a 75 compact bundle, such as is shown in Fig. 3, is produced. The paper is folded as compactly as possible by the use of the hands of the operator, but not folded as tightly as would be the case if compressed by machinery, as, when properly folded, spaces between the sheets for the reception of oil, as will hereinafter appear, are produced, whereas, if folded compactly by machinery, 80 the sheets composing the bundle would be 85 brought into close contact throughout their entire length and the oil spaces which are required would be eliminated.

I have found that mucilage such as commonly used upon gum strips, while soluble 95 in water is not soluble in the class of oils which I use and, therefore, find a gum strip, such as indicated, to be a very cheap, economical and convenient way of holding the package in form until saturated and have 100 shown this means in my drawings, although it is at once evident that other means, such as cord passed around the package, could be used if desired.

The package thus formed is charged with 105 the fuel or other like oil by inserting one end of the package in a vessel containing the oil and the paper of which the package is composed is thus thoroughly saturated with the oil and the interstices or chambers, 110 which, when the paper is folded as described, are produced throughout the pack-

age, are filled with oil. The package having thus been charged with oil its full capacity is allowed to drain for a sufficient length of time to permit the oil carried by 5 the end of the package which has been inserted in the oil chamber to be drained back into the oil receptacle, and the package is, after this treatment, stored within a suitable receptacle in readiness for use when desired. 10 I have found that, when the package has been thus stored for a suitable length of time, the package will thereafter remain in a solid, substantial form, even although the means for holding it together is dispensed 15 with.

In use in kindling fires, one or more of the packages are placed upon the grate and coal (either anthracite or bituminous) is placed directly upon the package, no other 20 kindling whatever being required. In burning, the outer portion of the bundle is first consumed, the oil contained within the outer spaces being first to ignite, while the heat imparted therefrom will serve to generate 25 gas from the oil contained within the inner portion of the bundle and the inner layers are in turn consumed, one after the other until the entire package is consumed, by which time the heat generated by the oil and burning gases serve to ignite the coal.

While I have described my invention in the nature of a fire kindling device, it is

also evident that it can be used as a fuel. The result of my experiments have demonstrated it is equally well adapted for fuel 35 purposes.

Having thus described my invention, what I claim to be new and desire to secure by Letters Patent is:—

1. An article of fuel comprising one or 40 more papers folded into a compact bundle, the paper composing the package and the spaces between the sheets of the package being filled with fuel oil or other oil of suitable body, viscosity, volatility and consistency, substantially as shown and described and for the purpose specified.

2. An article of fuel comprising a sheet or sheets of paper or other material of like 50 nature, folded into a compact bundle, the bundle being held in form by gummed strips or their equivalents, the package being saturated and the interstices between the sheets being filled with fuel oil or other oil of a suitable body, consistency, viscosity and volatility, substantially as shown and described and for the purpose specified.

In testimony whereof I hereunto affix my signature in the presence of two witnesses.

EDWARD J. DOLAN.
